UNITED STATES PATENT OFFICE

2,623,525

DEVICE FOR GENERATING FARADIC CURRENTS

Charles Love Strong, London, England

Application October 24, 1950, Serial No. 191,840

In Great Britain November 1, 1949

4 Claims. (Cl. 128—423)

1

This invention relates to electro-therapeutic apparatus such as is used for the treatment of injuries, rheumatism and other ailments by rhythmic muscular contractions effected by faradic currents. The chief object of the present invention is to provide apparatus which will enable treatment to be carried out at a point remote from the generator of the said faradic currents while completely under the control of the therapist. The apparatus thus lends itself particularly to the treatment of horses where it is impossible, or undesirable, for the apparatus generating the faradic currents to be present in the horse-box.

The apparatus for the treatment of injuries, rheumatism and other ailments by rhythmic muscular contractions effected by faradic currents according to the present invention comprises a vibrator for interrupting an electric current, a step-up transformer for stepping up the interrupted current and a resistor with a mechanically rotated arm driven by an electric motor for imparting a surge to the current during its application, and is characterised by the provision of a remote control unit adapted to be located at a point remote from the generator, said remote control unit being provided with means for switching the generator on and off, means for controlling the strength of the current applied to the patient and means for controlling the speed of the electric motor driving the resistor and mechanically rotated arm to vary the rate of surge.

Preferably the said remote control unit also includes a tell-tale lamp to indicate to the therapist that the generator is switched on, and the electric motor may also be adapted to drive a resistor and mechanically rotated arm included in the circuit of the tell-tale lamp to give an indication of the rate of surge to the therapist.

The remote control unit may be connected to the generator by means of a multi-wire cable and plugs and sockets so that, when it is not required to apply the treatment at a remote point, the cable may be detached and the remote control unit be plugged in to the generator to give a direct control at the generator.

In order that this invention may be the more clearly understood and readily carried into effect, reference may be made to the accompanying drawing, which is the circuit diagram of the preferred embodiment of electro-therapeutic apparatus according to the present invention.

Referring now to the accompanying drawing, the apparatus therein illustrated comprises a main generator A and a remote control unit B.

2

Electric power, conveniently from a six or twelve volt supply, is connected to the generator A at the point S, and the circuit is controlled by a switch 10 which is located in the remote control unit. When the switch 10 is closed the circuit of the relay 11 is completed, whereupon the relay operates to close three switches 12, 13 and 14. Similarly, when the switch 10 on the remote control unit is opened, the relay 11 functions to open the switches 12, 13 and 14. The switch 12 is adapted to connect an electric motor 15 (the purpose of which will be described hereinafter) across the input S in series with a rheostat 16 at the remote control unit. The speed of the motor 15 may thus be controlled by the rheostat 16 at the remote control unit. The switch 13 on the relay is adapted to close the circuit of a vibrator 17, similar to that used in car radio sets, the vibrator 17 being fed from a separate six volt or twelve volt battery 18. Vibrator 17 includes an additional separate winding terminated by a resistor or capacitor which partially determines the rate of vibration thereof. The vibrator 17 is connected to the two ends of the primary of a faradic step-up transformer 19 which is centre-tapped back to the vibrator circuit. The secondary of the transformer 19 is connected to the usual surge rheostat 20, which is driven by the electric motor 15, the circuit being completed through a potentiometer 21 located in the remote control unit B. The leads for the application of the faradic currents to the patient are connected to the terminals 22 or the plug and socket connection 23 which are paralleled across one end and the contact arm of the potentiometer 21. It will thus be seen that, in addition to being able to switch the generator on and off from the remote control unit, the therapist is also able to control at the remote point the rate of surge by controlling the speed of the motor through the intermediary of the rheostat 16 and the strength of the current applied to the patient by means of the potentiometer 21.

The third switch 14 of the relay is adapted to bring into circuit a variable rheostat 24 in the generator A which is connected in series with a tell-tale lamp 25 and control switch 26 at the remote control unit. The tell-tale lamp is connected across the input in series with the rheostat 24 and switch 26. The arm of the lamp rheostat 24 is driven by the electric motor 15 synchronously with the surge rheostat 20, and it will thus be seen that so long as the apparatus is functioning correctly the tell-tale lamp 25 on the remote control unit B will flash on and off

at the surge rate, it thus being not only a useful indication to the therapist that the generator A is functioning properly but also an indication to him of the rate of surge.

While in the treatment of animals it is desirable to have the generator A remote from the animal being treated, this is not in general necessary when human beings are being treated since human beings can safely be treated in close proximity to the generator. In order, therefore, to adapt the apparatus according to the present invention for use in such conditions, the remote control unit B is preferably coupled to the generator A through a multi-lead cable 30 having plug and socket connections indicated diagrammatically at 31 and 32, and the arrangement is such that, when desired, the extension cable 30, which may, of course, be of any desired length, may be removed and the remote control unit B plugged directly into, say, the top of a casing containing the generator A so that it may be operated to control the generator A from that point in the manner described above.

Although the apparatus has been described above as operating from a six or twelve volt supply, it may, if desired, be operated from the mains, the mains voltage being stepped down and, of course, rectified before it is fed to the vibrator.

The apparatus according to the present invention is simple to produce and easy to operate, it giving perfect control over the treatment at a point remote from the generator.

I claim:

1. Electro-therapeutic apparatus for the treatment of injuries, rheumatism and other ailments by rhythmic muscular contractions effected by faradic currents, comprising a generator unit including a vibrator for interrupting an electric current, a step-up transformer for stepping up the interrupted current and a resistor with a mechanically rotated arm driven by an electric motor for imparting a surge to the current during

its application to the patient, a remote control unit adapted to be located at a point remote from the generator of the said faradic currents, said remote control unit being provided with means for switching the generator on and off, means for controlling the strength of the current applied to the patient and means for controlling the speed of the electric motor driving the resistor with the mechanically rotated arm to vary the rate of surge.

2. Electro-therapeutic apparatus according to claim 1, further comprising a tell-tale lamp included in said remote control unit; a variable resistor connected to said tell-tale lamp for varying the brilliance thereof, said resistor having a mechanically rotated arm driven by said electric motor and connected to said lamp, whereby a therapist operating the apparatus will be given visual indication of the surge rate thereof.

3. Electro-therapeutic apparatus according to claim 2, in which the remote control unit is provided with a switch adapted to close the circuit of a relay at the generator, which relay, when actuated, is adapted to close the circuits of the vibrator, the electric motor and the tell-tale lamp resistor with a mechanically rotated arm.

4. Electro-therapeutic apparatus according to claim 2, in which said tell-tale lamp is connected to the circuit of said generator to indicate when said generator is switched on.

CHARLES LOVE STRONG.
